APPLYING PIGMENTS TO SHEET MATERIAL

Alfred Pierssene Battey, Eastcote, England, assignor to McCorquodale and Company Limited, London, England, a company of Great Britain, and Denis Kavanagh L'Estrange, Wanstead, Essex, England

Application March 22, 1940, Serial No. 325,470
In Great Britain April 6, 1939

17 Claims. (CL 91—47)

This invention relates to an improved method of applying pigment to the surface of a number of sheets of paper, cardboard, fabric or the like singly in succession, utilising an intermittently operating, e. g. a reciprocating, sheet feed mechanism, and to apparatus for carrying out the improved method.

In applying pigment to a number of paper or other sheets singly in succession by the method according to the present invention, a sheet is fed by means of said mechanism to a position opposite a matrix having recesses in the face thereof, and the sheet is then clamped against the recessed face of said matrix and pigment applied to the surface of the sheet by leading the pigment under pressure from a suitable source through conduits leading through the matrix to the recesses in the face thereof, thereafter the sheet is parted from the matrix but retained in a horizontal position immediately beneath the matrix during further movement of the sheet feed mechanism, the sheet with the pigment applied being finally removed from beneath the matrix during a subsequent movement by the sheet feeding means for feeding the next succeeding sheet beneath the matrix.

In the preferred arrangement the sheet feeding means is of the type adapted to make straight line reciprocating movements and in accordance with the invention said reciprocating means may operate both to feed the sheets beneath the matrix and also to remove them from beneath the matrix after the pigment has been applied.

By the method according to the invention, the pigment is applied to areas on the sheet as defined by the boundaries of the recesses in the face of the matrix and after the sheet is disengaged from the matrix it is maintained in position beneath the matrix for an appreciable period of time so that drops or strings of pigment adhering to the matrix will fall into correct position on the sheet, whilst at the same time a high singly in succession, utilising an intermittently according to the present invention, a sheet is fed by means of said mechanism to a position line reciprocating movements and in accordance with the invention the sheet feeding means may operate both to feed the sheets beneath the matrix and also to remove them from beneath the matrix after the pigment has been applied.

The invention further consists in an apparatus for applying pigment to the surface of a number of sheets of paper, cardboard, fabric or the like singly in succession comprising intermittently operating sheet feeding means, a matrix with recesses in the face thereof, against which a sheet, fed by movement of the sheet feeding means to a

position opposite the matrix, is adapted to be clamped, conduits adapted to lead pigment under pressure to the recesses in the face of the matrix and on to defined areas of the surface of the sheet, and holding means adapted to retain the sheet in position immediately beneath the matrix after being parted therefrom and during further movement of the sheet feeding means.

The invention is illustrated by way of example in the accompanying drawings, the embodiment illustrated employing a reciprocating intermittent sheet feed mechanism.

In the drawings

Fig. 1 is a general side elevation of a complete machine according to the invention,

Fig. 2 is an end elevation looking from the right in Fig. 1,

Fig. 3 is a plan view,

Fig. 4 is a perspective view of the reciprocating sheet feed means,

Fig. 5 illustrates on a larger scale a part of the mechanism for driving the sheet feed means,

Fig. 6 illustrates a detail of the sheet feed means looking from the far side of Fig. 4,

Figs. 7 and 8 show further details,

Figs. 9 and 10 are views in elevation and plan respectively and on a larger scale, illustrating the mechanism for clamping the sheet against the matrix and for applying pigment to the clamped sheet,

Figs. 11 and 12 show details,

Fig. 13 illustrates means for maintaining a sheet in position beneath the matrix whilst the reciprocating sheet feed means make a return movement,

Figs. 14 and 15 are views in sectional elevation of the machine showing the driving mechanism for moving parts disposed adjacent opposite sides of the machine,

Fig. 16 is an enlarged sectional plan of the operating mechanism.

Referring to the drawings, 1 represents a base frame structure in which are mounted four vertical columns 2 adapted to make rising and falling movements in suitable guides.

The columns 2 are disposed at the four corners of a rectangle, considered in plan, and they are connected at their lower ends to a frame 3 which is adapted to be raised and lowered by toggles 4 connected in pairs at opposite sides of the machine by the bars 5 which in turn are connected by links to a spindle 154 carried by levers 155 pivoted on an axis extending transversely of the machine, which levers 155 are

adapted to be rocked by links 31 moved by cams on a camshaft 32 in the machine.

The columns 2, at their upper extremities support a closed box-like structure 6 containing a number of open receptacles 7 for the pigment, and the interior of the box 6 is kept under pressure through a flexible compressed air pipe 8. The columns 2 also support, intermediate their length, a rigid frame structure 9, to the underside of which are connected a pair of stiff bars 10 forming a support for a horizontally disposed metal block or matrix 11 fixed to the underside of said bars 10. It will readily be seen that the closed box 6, the rigid frame structure 9 and the matrix 11 are moved up and down with the rising and falling columns 2.

This matrix 11, a portion of which is shown in Fig. 12, is provided on the underside with a machined face in which are formed a series of suitably disposed shallow recesses 12.

The body of the matrix 11 is pierced at the back of each recess 12 as shown at 13, and the upper end of each aperture is internally screw threaded to receive the lower threaded end of a metal cylinder 14 preferably with the interposition of a leather washer 15. A metal tube 16 is mounted for longitudinal movement within each cylinder 14 and a valve head 17 at the lower end of each tube 16 engages a seating formed by the upper end of the small diameter portion of aperture 13. A downwardly directed cup washer 18 is mounted on the exterior of the tube 16 and fits the interior of the cylinder 14, and between the upper side of the washer 18, or a backing ring 19 therefor, and a centralising gland 20 at the top of the cylinder 14 extends a compression spring 21 surrounding tube 16. A further compression spring 22 surrounds the tube 16 and extends between a shoulder at the lower end thereof and a sliding coned member 23 adapted to spread the cup washer 18.

Ports 24 are provided in the walls of the tube 16 leading to the space between the tube 16 and the cylinder 14 beneath the cup washer 18.

Each tube 16 is connected through a flexible conduit 25 with one of the pigment receptacles 7 in the box 6, and it will readily be seen that by raising the tubes 16 relatively to the cylinders 14, pigment will be permitted to flow to the recesses 12 in the face of the matrix.

The upper ends of the tubes 16 extend through apertures or slots in stiff bars 26 (Figs. 10 and 12) which are in turn fixed to a pair of bars 27 extending longitudinally of the frame structure 9 and arranged for up and down movement parallel to themselves in guides in said frame structure. The ends of tubes 16, above the bars 26 are provided with collars or nuts 16' which are adjusted in position longitudinally on the tubes, so that in the closed condition of the valves, there is a small clearance between the nuts 16' and the upper surfaces of the bars 26 (Fig. 12).

The bars 27 are provided on their undersides with inclined surfaces 28 (Fig. 9) which engage with corresponding inclined surfaces 29 on bars 30 arranged for longitudinal sliding movements in the frame structure 9. These movements are imparted to the bars 30 in one direction from a rocking shaft 31 on the frame structure through the medium of lugs 32 fast on said shaft and push rods 33 extending between said lugs 32 and the ends of the bars 30, and in the other direction by compression springs 34 extending between fixed abutments 35 on the frame structure and lugs 36 on the underside of the bars 30, said springs 35

being supported by guide rods 35' fixed to the abutments 35 and extending through the lugs 36.

It will readily be seen that when shaft 31 is rocked in a manner yet to be described, bars 30 will be moved to the right in Fig. 9 and bars 27 raised to lift bars 26 relatively to the frame structure 9 and when the collars 16' are engaged by the bars 26, all the tubes 16 of the pigment valves will be lifted within the cylinders 14 to permit the flow of pigment to the recesses 12 in the face of the matrix.

On one end of the base frame structure 1 is mounted a lay board 37 (Figs. 1, 3, 14 and 15) preferably at an inclination as shown and capable of being tilted about an axis 37' to raise and lower the forward edge thereof, and the sheets of paper or other material to which pigment is to be applied are placed thereon singly by hand or by any suitable known automatic means, and stops or gauges 38 are provided adjacent the forward edge of said lay board to accurately locate a sheet thereon.

A pair of parallel guides 39 are supported by the base frame structure 1 and extend longitudinally of the machine between the pairs of columns 2 at opposite sides of the machine, and the sheet conveying means is adapted to make horizontal reciprocating movements on these guides 39.

The sheet conveying or feeding means comprises a heavy metal table 40 (Figs. 1 and 2 and 4 to 7) which is arranged to slide on rollers 41 resting upon the above mentioned guides 39, between two positions in one of which the table extends beneath the lay board 37 as shown in dotted lines in Fig. 1, and in the other of which it lies beneath the matrix 11.

The table 40 at the end away from the lay board 37 is provided with a recessed extension as clearly shown at 42 in Fig. 4, which extension may be formed as an integral casting with the table 40, and the side walls 43 of this recess support longitudinally extending arms 44 between which are mounted shafts 45 carrying rollers 46 supporting endless bands or tapes 47 the upper runs of which are in the plane of the top of table 40.

The shafts 45, at one end outside one wall 43, carry toothed sprockets 48 which engage with a driving chain 49 (Fig. 6) the ends of which are fixed to an anchorage 50 (Figs. 3 and 6) on the frame of the machine.

The sprockets 48 include freewheels and the arrangement is such that as the table 40 is moved in one direction, i. e. towards the lay board 37, the shafts 45 are rotated to move the upper runs of the tapes 47 in the opposite direction relatively to said table, whilst during movement of the table 40 away from the lay board the tapes remain stationary relatively to the table.

Between the walls 43 and near the edge of the table 40 also extends a rocking shaft 51 carrying grippers 52, and this shaft is adapted to be rocked at appropriate moments and in a manner yet to be described so that when the table 40 is beneath the lay board 37 they grip the leading edge of the sheet of paper on the lay board, to the surface of the table away from the lay board and the sheet is taken with the table, whilst when the table reaches its position beneath the matrix 11, said grippers may be moved from engagement with the sheet to a position where they lie below the level of the table top as shown in dotted lines in Fig. 5.

The means for reciprocating the table 40 and the connected parts is as follows:

In the base frame structure is mounted a fixed rack 53 on which rolls a rack wheel 54. This rack wheel in turn engages with a further rack 55 provided on the underside of the table (Fig. 2).

The rack 55 beneath the table 40 is capable of sliding movements relatively thereto, being carried with its edges in guides 56 fixed to the underside of the table, and the arrangement is such that the rack 55 and the table may be connected and the table moved by and with the rack 55, or they may be disconnected so that the table may remain stationary whilst the rack is moved in the guides 56. For this purpose a shaft 57 is carried in bearings in the table extension 42, one end of said shaft extending through one of the walls 43. This shaft carries rigidly mounted pawls 58 (Fig. 5) the ends of which are movable in apertures 59 in the floor of the extension 42 and may make abutting engagement with the ends of suitably disposed slots 60 in the body of the rack 55. By rocking the shaft 57, the pawls 58 may be moved to the position shown in dotted lines in Fig. 5 so that movements of the rack 55 to the right in that figure are not transmitted to the table 40. When the rack 55 is in the position shown in Fig. 5 relatively to the table 40, the left hand end of the rack engages a suitable stop 61, Fig. 15, beneath the table so that the table is constrained to move in both directions with the rack 55.

It will readily be seen that when the rack 55 and table 40 are connected, the extent of the reciprocating movement of the table, due to the rolling rack wheel 54, will be double that of said rack wheel on the fixed rack 53.

The machine is driven for example from an electric motor 62, this motor, through a belt and pulley, driving a shaft 63 mounted in bearings in the frame of the machine (Figs. 1, 15 and 16). This shaft 63 is geared to a pair of toothed wheels 64 mounted on the adjacent ends of two spaced co-axially mounted shafts 68 and connected together by a crank pin 65 to which is connected a rod 66, the other end of which is in the form of a yoke embracing the rack wheel 54 and connected with the axle pin 67 thereof. A toothed wheel 68 rigid with one of the shafts 68 is geared to a camshaft 69 bearing a number of rigidly mounted cams for operating component parts of the machine in timed relationship.

In the case illustrated, shaft 68 makes one revolution for every two revolutions of the shafts 68.

In operation the shaft 63 rotates wheels 64, and the pawls 58, being in the position of engagement with rack 55 as shown in full lines in Fig. 5, the table moves into the position beneath the lay board as shown in dotted lines in Fig. 1, the lay-board being tilted with its forward edge raised during this movement and being lowered when the table is in position beneath it. During at least a part of the movement of the table towards this position the grippers 52 are in the position where they lie below the level of the top of the table. The grippers are retained in this position by the engagement of a toothed wheel 78 fast on the end of shaft 51 with a toothed segment 76 (Figs. 8 and 14) on one end of a lever 71 pivoted on the outside of one of the walls 43 of the table extension; the other end of this lever 71 is provided with a roller 72 making engagement with the underside of a horizontal bar 73 extending longitudinally at one side of the machine.

This bar 73 is adapted to make rising and falling movements parallel to itself, being connected

with the corresponding limbs of two similar bell crank levers 74 similarly pivoted on the machine. These levers 74 are constrained to move in unison by a link 75 and they are rockable through a further link 76 and a lever 77 from a cam on camshaft 69 to raise or lower the bar 73.

As the table 40 approaches the completion of the movement towards the above described position beneath the lay board, this cam operates to raise the bar 73 and the lever 77 is permitted to rock and the gripper carrying shaft 51 to rotate under the urge of a spiral spring 79 at one end of said shaft (Fig. 4) and at the instant when the table reaches the end of its travel, the grippers move into position to grip the leading edge of the sheet of paper on the now lowered lay board, to the surface of the table.

The gauges 38 at the edge of the lay board are so disposed that the leading edge of the paper sheet projects slightly beyond the edge of the table 40. The up and down tilting movement of the lay board is effected through a lever and linkage system 88 from a cam on the camshaft 69, and this lever and linkage system also serves to raise the gauge 38, after the lay board has been lowered, from the path of the paper sheet. The gauge 38 having been raised, the movement of the table 40 in the direction away from the lay board, together with the sheet of paper commences.

This movement continues until the table with the sheet of paper thereon comes beneath the matrix 11. Since drive of the wheels 64 is continuous, it is necessary, in order that the table 40 with the sheet thereon may remain stationary beneath the matrix 11, to uncouple said table from the rack 55.

For this purpose the end of the shaft 57 carrying the coupling pawls 58, is provided with a lever 88 bearing a roller 89 and this roller, when the table 40 is beneath the matrix, engages the upper surface of one limb of a cranked lever 90 pivotally mounted on the frame of the machine, Fig. 4. This lever 90 is adapted to be rocked through a link 91 and lever 92 from a cam on the camshaft 69 to in turn rock the lever 88 and shaft 57 to disengage the coupling pawls 58 from the slots in the rack 55. Thus the rack 55 is freed to slide in the guides on the underside of the table 40.

To avoid the possibility of movement of the table 40 due for example to friction with the rack, a latch bar 93 may be provided on the machine, said bar being pivoted as at 94 and having a projection 95 on its free end for engagement with the underside of the above mentioned cam controlled lever 90 and being urged upwards by a spring 96 in such manner that the upturned end 97 of said bar 93 enters a notch in the table 40 when the lever 90 moves into position to uncouple the table from the rack 55 as described above.

During the travel of the table 40 toward the matrix the columns 2 commence to move downwards in their guides through the straightening of the toggles 4. The operation of the toggles is effected through links 5, shaft 154 and link 81, the latter being moved by cams on camshaft 69 in a manner to be described later. Downward movement of the columns 2 continues until the face of matrix 11 contacts firmly with the sheet of paper on the table 40, said table by this time having come to rest and been locked in position beneath the matrix in the manner described above.

The paper sheet is now ready to receive the pigment.

To permit the pigment to flow, the tubes 16 of all the valves in the back of the matrix 11 are raised by rocking the shaft 31 to move push rods 33 and bars 30 to raise bars 27 and 28 in the manner previously described, and the rocking of shaft 31 is effected by the engagement of the end of a pawl 83 carried at the end of a pivotal cam actuated lever 84, with a notch in a lug 85 fast on the shaft 31. The lever 84 is actuated in appropriate timed sequence by a link 86 and lever 87 from a cam on camshaft 88.

Thus pigment flows under pressure from the receptacles 1, through the conduits 25, the valves 16, 14 and the body of the matrix to the recesses 12.

After a given short interval as determined by the cam controlling the lever 84, the shaft 31 is rocked in the reverse direction under the urge of return springs 84, and the pigment valves close. Thereafter the columns 2 are caused to rise and the paper sheet with the pigment applied in areas sharply defined by the boundaries of the recesses in the face of the matrix 11, is parted from the face of the matrix and rests upon the table.

A number of small spring pressed plungers 11' may be provided in suitable apertures in the matrix 11 to push the sheet away from the face of the matrix as the latter rises.

Pigments are usually of a tacky or viscous nature and it is found that when the paper or other sheet is parted from the matrix, strings of the material are formed between the matrix and the paper and drops adhere to the matrix itself and then fall on to the paper. It becomes imperative, therefore, to maintain the paper in exact position beneath the matrix for such an interval of time as will enable such drops or strings to fall on to the correct areas.

In accordance with the invention this is achieved but without loss of time and output, since the feed table 48 is permitted to return towards the lay board during this interval of time to receive the next sheet.

Shortly after the sheet has been effectively gripped between the plate 48 and the matrix 11, the horizontal bar 73 is moved downwards by its control cam and the grippers 52 are caused to rock and to assume the position below the level of the surface of the table 48 as shown in dotted lines in Fig. 5.

For the purpose of retaining the paper sheet in position beneath the matrix after the latter has been raised there is provided a cradle-like device 160 of the form shown in Fig. 13. This device 160 extends across the machine, being suspended by the two arms 161, and in such a manner as to be rockable about a horizontal axis in fixed brackets 162 on the machine, between the two positions shown in full and dotted lines in Fig. 9 by means of a link 163 and a lever 164 operated by a cam on shaft 89. Between the ends of the member 160 extend a pair of parallel spindles 165 geared together for rotation in unison as shown at 166 and having fingers 167, 168 fixedly mounted in such a manner as to form pairs of co-operating grippers. Springs 88 are connected between arms 160 fast on the spindles 165 and tend to rotate the spindles so as to move the pairs of fingers 167, 168 together into the gripping position as shown in Fig. 13.

One of the spindles 165 carries at its end, outside the cradle member 160, a lever 161 bearing

a roller 162 at its end. On a fixed pivot 163 on the machine frame is mounted a bell crank lever 164 adapted to be rocked through a given angle by a link 165 and lever 166 from a cam 167 on a camshaft 168 geared to camshaft 89.

Prior to the upward movement of the matrix 11, the grippers 52 having been rocked to the position below the surface of the table 48 as described above, the cradle-like member 160 is swung counterclockwise about its pivotal axis 162, and during this movement the roller 162 engages the edge of one limb of lever 164 so that the spindles 165 are rotated to part the grippers 167, 168, and the member 160 comes to rest with the grippers 167 above and the grippers 168 below the leading edge of the sheet of paper which projects beyond the edge of table 48.

The bell crank lever 164 is now rocked to lower roller 162 on lever 161, and the grippers 167 and 168 are permitted to grip the edge of the paper sheet between them so that they serve to hold it in the position below the matrix after the latter has been raised.

As soon as the matrix commences to rise, the bell crank lever 90 is rocked to disengage the latch 97 from the table 48 and the upper rack 55 which is now in an appropriate position beneath the table 48 is re-engaged therewith through the dropping of the ends of the pawls on the extension of the table into the slots 60 in said upper rack.

Thereupon the table 48 moves back with the rack 55 to the position beneath the again upwardly tilted lay board, and thereafter the lay board is again tilted downwards and the grippers 52 on the table take a grip on the leading edge of the next succeeding sheet of paper.

During this movement to the position beneath the lay board, the table 48 takes with it the extension and the endless tapes or bands 47, and during the movement in this direction the shafts 45 are rotated by the chain 49 so that the upper runs of the bands are moved in the direction away from the table and the arrangement is such that there is no relative sliding movement between the tapes and the sheet, so that the latter therefore remains entirely undisturbed.

As the table 48 commences its next feed movement towards the matrix the cradle member 160 is swung clockwise about its pivot, the grippers 167, 168 momentarily maintaining a grip on the sheet in order to impart an initial movement thereto in the direction of movement of the table 48. The grippers are then opened by the rocking of bell crank lever 164 and lever 161 and swung out of the path of the sheet which now rests upon the belts 47. In this direction of movement of the table, the shafts 45 are not rotated by the chain 49 in view of the employment of the freewheel sprockets 48, so that the sheet with the pigment applied thereto is carried away from beneath the matrix 11 at the speed of travel of the table, whilst the next succeeding sheet is fed into position beneath said matrix, and the described cycle of operations is repeated. The treated sheet may be removed from the tapes 47 by hand or it may remain thereon throughout a further complete reciprocation of the feeding means so that it is fed off the tapes, for example on to a suitable conveyor not shown.

It is to be understood that the table 48 may be held disconnected from the upper rack bar for one or a number of reciprocating movements of said rack bar as desired, by the utilisation

of an appropriate gear ratios between the shafts 69 and 108.

It is also to be understood that suction and like devices may be employed as an alternative to the mechanical grippers described above for securing the sheets to the sliding table 40 and for holding the sheet beneath the matrix whilst the table is moving.

The improved machine also includes means whereby the movement of the matrix 11 towards the table 40 and the opening of the pigment release valves shall not occur when the table moves to the position beneath the matrix without a sheet of paper, and so that pigment shall not be deposited on the surface of the table.

The means for this purpose is illustrated in Fig. 15. The link 81 operating the toggles 4 is connected to one arm 109 of a two armed lever mounted for rocking movement on a fixed shaft 110, which forms the axis of a two armed cam operated lever 82, and the other arm 111 of said lever carries a pivoted pawl 112. This pawl is adapted to rest under the pull of a light spring 112', with its operative end against an abutment surface formed by a notch 113 on one arm of the lever 82.

On a further shaft 115 is mounted a lever 116, one limb of which carries a roller 117 for engagement by a cam on shaft 69, whilst the other end supports a rocking pawl 118. This pawl is provided on its underside with a shoulder 119 adapted to engage with a pin 120 on a further lever 121 rockable on shaft 115. This lever 121 is connected by a link 122 with a lever 123 pivoted at 124, the free end of which is capable of engaging a roller 125 on pawl 112 to rock the latter from engagement with abutment 113.

The lever 118 is arranged to be rocked by a cam on shaft 69 once during each cycle of operation of the machine and the pawl 118 carried thereby tends to move by gravity into the position where the shoulder 119 engages with the pin 120 on the lever 121. During normal operation however, a roller 126 on pawl 118 (Fig. 15) rests upon the edge of a pivoted lever 127, one end of which is weighted as shown at 128 in such a manner as to tend to maintain the shoulder of pawl 118 out of engagement from pin 120. The weight 128 rests upon the upper end of a rod 129 and tends to thrust it downwards.

It will readily be seen that if rod 128 is thrust upwards, lever 127 will be rocked against gravity and the pawl 118 will no longer be supported by lever 127 but will rest with its lower edge on the pin 120, and in due time, during the movement of lever 118, the shoulder 119 will engage the pin 120, so that lever 121 will be moved by and with lever 116 to impart a thrust to rod 122, thereby rocking lever 123 to knock pawl 112 clockwise about its pivot against spring 112' to disengage the end thereof from the notch 113 on lever 82. The next cam controlled movement of lever 82, therefore, is not transmitted to lever 111 and the toggles and the pillars 2 and parts carried thereby, remain stationary. Since the frame structure 9 remains stationary, the next rocking movement of the pigment valve operating lever 84 does not result in contact of pawl 83 with lug 85 and the valves therefore remain unoperated.

The upward movement of the rod 128 is arranged to take place whenever the table 40 is about to move from beneath the lay board without a sheet of paper. For this purpose there is

provided at one side of the lay board (Fig. 15) a bracket 132 on which is mounted a pivoted lever 133 extending over the lay board. To the lower end of the lever 133 is pivoted a finger 134 the lower end of which is adapted to slide longitudinally of the lay board in alignment with a slot 135 formed in said lay board. The upper end of the lever is connected by a rod 136 to a pivoted lever 137 which is adapted to be rocked to and fro once during each cycle of operations, in one direction by a cam 138 and in the other by a spring 139. A further lever 140 is pivoted at 141 on the machine frame and bears a roller 142 adapted to run on a notched cam 143. This lever 140 is urged towards the cam by a spring 144 but the free end of said lever overlaps the upper end of lever 137 when the latter has moved to its maximum extent in a clockwise direction as shown in dotted lines in Fig. 15. The other end of lever 140 is connected by a rod 145, a bell crank lever 146 and a further rod 147, with rocking lever 131.

When a sheet of paper is fed in normal manner on to the lay board, the lower end of finger 134 slides freely over the surface of the sheet of paper as lever 137 is moved clockwise by the spring 139. The upper end of lever 137 therefore takes position beneath the end of lever 140 and the latter is prevented from falling when the notch in cam 143 comes opposite roller 141.

Should no sheet of paper be fed to the lay board, the finger in its movement towards the edge of the board, drops into slot 135 so that its sliding movement is arrested and it thereby prevents lever 137 making its full movement in a clockwise direction under the urge of spring 139. As a consequence lever 140 rocks under the pull of spring 144 when the notch in cam 143 comes opposite roller 141, and rod 145, bell crank lever 146 and rod 147 are moved to operate rocking lever 131 and to disengage pawl 112 from notch 113 as previously described, so that the matrix is not lowered and the pigment valves are not operated, the table 40 making an idle reciprocation. The placing of a sheet of paper on the lay board frees the finger 134 from slot 135 and normal operation of the machine is resumed. A stop 148 at the end of the toggle operating linkage engages an abutment 149 on the machine frame to ensure that even should the matrix and other rising and falling parts be moved down independently by hand for example, when making adjustments, the pawl 112 can always drop into engagement with notch 113 when required to do so.

Furthermore, the pawl 83 on the pigment release valve operating lever 84 is arranged for clockwise pivotal movements on said lever against a spring, so that should the pawl be in its valve releasing position and the vertically moving columns and parts carried thereby be moved downwards, the pawl can yield until the rocking lever 84 is moved.

A hand lever 31' is provided to enable shaft 31 to be rocked at any time by hand, but usually when the machine is stationary, to clear the valves for example.

A pedal 150 is provided on lever 131 to enable the transmission pawl to be thrown out of action at any time by an operator and a latch lever 151 is also provided pivoted on lever 131, for engagement by a shoulder 152 with a fixed pin 153 carried by a part of the machine frame to retain the pawl 112 in its disengaged position so that the matrix can be prevented from moving down-

wards for any desired period whilst the plate is moving.

Means are provided to enable the position of the matrix and other rising and falling parts to be adjusted to vary the pressure exerted by the matrix on the paper or other sheet on the table 40.

For this purpose, frame structure 3 at the lower ends of the columns 4 mounts four rotatable sleeves 169 into which are screwed the lower ends of the columns 4. The sleeves 169 are each provided on the exterior with helical gears which are adapted to be rotated in unison through suitable gearing from a shaft 170 mounted in bearings on the said moving frame structure 3, and provided with a hand crank 171.

This arrangement enables the distance of the matrix 11 from the frame structure 3, and thereby the closeness of the approach of the matrix towards the surface of the table 40, to be accurately controlled.

In practice it is usually found desirable to provide a slightly yielding cushion such as one or more layers of paper between the surface of the table 40 and the sheet of paper or other material which is to receive the pigment.

In the above described arrangement the sliding table 40 forms the support for the sheet when under the pressure of a rising and falling matrix 11.

In the example described above and illustrated in the drawings, the clamping of the sheet in the position against the matrix to receive the pigment is achieved by subjecting the matrix to reciprocating up and down motion relative to the table, but it is to be understood that other arrangements may be employed for this purpose.

Similarly, although the feed of sheets, in the example described, is effected by means of a reciprocating table, alternative forms of intermittent sheet feeding means may be employed.

I claim:

1. Apparatus for applying pigment to the surface of a number of sheets of paper, cardboard, fabric or other sheet material singly in succession, comprising a matrix having recesses in the face thereof, intermittently operating sheet feeding mechanism adapted to feed sheets singly to a position opposite the face of said matrix, means to effect relative movement between said matrix and a sheet fed by said feeding mechanism first to bring said fed sheet into clamped surface contact with the face of said matrix and subsequently to release it therefrom, conduits leading pigment under pressure through said matrix to the recesses in the face thereof and on to the sheet, whilst the sheet is in the clamped position, and means for retaining the sheet in position vertically beneath said matrix after the sheet has been parted therefrom and during further movement of said sheet feeding mechanism and means whereby the sheet is moved from beneath said matrix during movement by the sheet feeding mechanism for feeding the next succeeding sheet to said position opposite the matrix.

2. Apparatus for applying pigment to the surface of a number of sheets of paper, cardboard, fabric or other sheet material singly in succession, comprising a matrix having recesses in the face thereof, reciprocating sheet feeding means adapted, during movement in one direction, to feed sheets singly to a position opposite the face of said matrix, means to effect relative movement between said matrix and a sheet fed by said feeding means first to bring said fed sheet into

5 clamped surface contact with the face of said matrix and subsequently to release it therefrom, conduits leading pigment under pressure through said matrix to the recesses in the face thereof and on to the sheet whilst the sheet is in the clamped position, and means for retaining the sheet in position vertically beneath said matrix after the sheet has been parted therefrom and during further movement of the reciprocating sheet feeding means and means whereby the sheet is moved from beneath said matrix after being released by the retaining device and during a subsequent movement of said reciprocating sheet feeding means for feeding the next succeeding sheet to the position opposite said matrix.

3. Apparatus for applying pigment to the surface of a number of sheets of paper, cardboard, fabric or other sheet material singly in succession, comprising a matrix having recesses in the face thereof, reciprocating sheet feeding means adapted, during movement in one direction, to feed sheets singly to a position opposite the face of said matrix, means to effect relative movement between said matrix and a sheet fed by said feeding means first to bring said fed sheet into 10 clamped surface contact with the face of said matrix and subsequently to release it therefrom, conduits leading pigment under pressure through the matrix to the recesses in the face thereof 15 and on to the sheet whilst the sheet is in the clamped position, and means for retaining the sheet in position vertically beneath said matrix after the sheet has been parted therefrom and during further movement of said reciprocating sheet feeding means first to bring said fed sheet into 20 clamped surface contact with the face of said matrix and subsequently to release it therefrom, conduits leading pigment under pressure through the matrix to the recesses in the face thereof 25 and on to the sheet whilst the sheet is in the clamped position, and means for retaining the sheet in position vertically beneath said matrix after the sheet has been parted therefrom and during further movement of said reciprocating sheet feeding means 30 and on to the sheet whilst the sheet is in the clamped position, and means for retaining the sheet in position vertically beneath said matrix after the sheet has been parted therefrom and during further movement of said reciprocating sheet feeding means, and means carried on the reciprocating sheet feeding means and adapted to remove the sheet from beneath said matrix 35 during a subsequent movement of said reciprocating sheet feeding means in the direction for feeding the next succeeding sheet to said position opposite said matrix.

4. Apparatus for applying pigment to the surface of a number of sheets of paper, cardboard, fabric or other sheet material singly in succession, comprising a horizontally reciprocating table, a matrix having recesses in the face thereof, mechanism for moving said matrix vertically towards and away from said table so as to clamp a sheet, fed by the table to a position opposite 45 said matrix, between the table and the face of said matrix, conduits leading pigment under pressure through said matrix to the recesses in the face thereof and on to the sheet whilst the sheet is in the clamped position and means for 50 retaining the sheet in position vertically beneath said matrix, after the sheet has been parted therefrom upon a rising movement of said matrix, and during further movement of said reciprocating table and means on said reciprocating table 55 adapted to move the sheet from beneath said matrix during a subsequent movement of the table in the direction to feed the next succeeding sheet to the position opposite said matrix.

5. Apparatus for applying pigment to the surface of a number of sheets of paper, cardboard, fabric or other sheet material singly in succession, comprising a matrix having recesses in the face thereof, reciprocating sheet feeding means adapted, during movement in one direction, to feed sheets singly to a position opposite the face of said matrix, means to effect relative movement between said matrix and a sheet fed by said feeding means first to bring said fed sheet into 70 clamped surface contact with the face of said matrix and subsequently to release it therefrom,

conduits leading pigment under pressure through said matrix to the recesses in the face thereof and on to the sheet whilst the sheet is in the clamped position, gripping devices movable relatively to said matrix and reciprocating sheet feeding means and adapted to make gripping engagement with an edge of the clamped sheet projecting from beneath said matrix to retain the sheet in position vertically beneath said matrix after the sheet has been parted therefrom and during further movement of said reciprocating sheet feeding means, and means whereby the sheet is moved from beneath said matrix after being released by said gripping devices and during a subsequent movement of said reciprocating sheet feeding means for feeding the next succeeding sheet to said position opposite said matrix.

6. Apparatus for applying pigment to the surface of a number of sheets of paper, cardboard, fabric or other sheet material singly in succession, comprising a matrix having recesses in the face thereof, reciprocating sheet feeding means adapted, during movement in one direction, to feed sheets singly to a position opposite the face of said matrix, means to effect relative movement between said matrix and a sheet fed by said feeding means first to bring said fed sheet into clamped surface contact with the face of said matrix and subsequently to release it therefrom, conduits leading pigment under pressure through said matrix to the recesses in the face thereof and onto the sheet whilst the sheet is in the clamped position, gripping devices mounted for rocking movements about an axis disposed transversely of the apparatus between one position out of the plane of the sheet of paper clamped against said matrix and another position where said gripping devices make gripping engagement with an edge of the clamped sheet projecting from beneath said matrix to retain the sheet in position vertically beneath said matrix after the sheet has been parted therefrom and during further movement of said reciprocating sheet feeding means, and means whereby the sheet is moved from beneath said matrix after being released by said gripping devices and during a subsequent movement of said reciprocating sheet feeding means for feeding the next succeeding sheet to the position opposite said matrix.

7. Apparatus for applying pigment to the surface of a number of sheets of paper, cardboard, fabric or other sheet material singly in succession, comprising a matrix having recesses in the face thereof, reciprocating sheet feeding means adapted, during movement in one direction, to feed sheets singly to a position opposite the face of said matrix, means to effect relative movement between said matrix and a sheet fed by said feeding means first to bring said fed sheet into clamped surface contact with the face of said matrix and subsequently to release it therefrom, conduits leading pigment under pressure through said matrix to the recesses in the face thereof and onto the sheet whilst the sheet is in the clamped position, a cradle adapted to rock about an axis disposed transversely of the apparatus, pairs of gripping fingers carried by said cradle and adapted to engage and grip an edge of the clamped sheet projecting from beneath the matrix to retain the sheet in position vertically beneath said matrix after the sheet has been parted therefrom and during further movement of said reciprocating sheet feeding means, and means whereby the sheet is moved from beneath

5 said matrix after being released by said gripping devices and during a subsequent movement of said reciprocating sheet feeding means for feeding the next succeeding sheet to the position opposite said matrix.

8. Apparatus for applying pigment to the surface of a number of sheets of paper, cardboard, fabric or other sheet material singly in succession, comprising a matrix having recesses in the face thereof, intermittently operating sheet feeding mechanism adapted to feed sheets singly to a position opposite the face of said matrix, means to effect relative movement between said matrix and a sheet fed by said feeding mechanism first to bring said fed sheet into clamped surface contact with the face of said matrix and subsequently to release it therefrom, conduits leading pigment under pressure through said matrix to the recesses in the face thereof and onto the sheet whilst the sheet is in the clamped position, and means for retaining the sheet in position vertically beneath said matrix after the sheet has been parted therefrom and during further movement of said sheet feeding mechanism, and thereafter to impart a movement to the sheet in a direction to remove it from the position opposite said matrix.

9. Apparatus for applying pigment to the surface of a number of sheets of paper, cardboard, fabric or other sheet material singly in succession, comprising a matrix having recesses in the face thereof, intermittently operating sheet feeding mechanism adapted to feed sheets singly to a position opposite the face of said matrix, means to effect relative movement between said matrix and a sheet fed by said feeding mechanism first to bring said fed sheet into clamped surface contact with the face of said matrix and subsequently to release it therefrom, conduits leading pigment under pressure through said matrix to the recesses in the face thereof and onto the sheet whilst the sheet is in the clamped position, and means for retaining the sheet in position vertically beneath said matrix after the sheet has been parted therefrom and during further movement of said sheet feeding mechanism, and thereafter to impart an initial movement to the sheet in a direction to remove it from the position opposite said matrix and means moving in conjunction with said sheet feeding means whereby the movement of the sheet in this direction is continued by and during movement by said sheet-feeding means for feeding the next succeeding sheet to the position opposite said matrix.

10. Apparatus for applying pigment to the surface of a number of sheets of paper, cardboard, fabric or other sheet material singly in succession, comprising a horizontally reciprocating table, a matrix having recesses in the face thereof, mechanism for moving said matrix vertically towards and away from said table so as to clamp a sheet, fed by said table to a position opposite said matrix, between said table and said face of said matrix, conduits leading pigment under pressure through said matrix to the recesses in the face thereon and onto the sheet whilst the sheet is in the clamped position, means for retaining the sheet in position vertically beneath said matrix, after the sheet has been parted therefrom upon a rising movement of said matrix, and during further movement of said reciprocating table and means adapted to move the sheet from beneath said matrix during a subsequent movement of said table in the direction to feed the

next succeeding sheet to the position opposite said matrix.

11. Apparatus for applying pigment to the surface of a number of sheets of paper, cardboard, fabric or other sheet material singly in succession, comprising a horizontally reciprocating table, a matrix having recesses in the face thereof, mechanism for moving said matrix vertically towards and away from said table so as to clamp the sheet, fed by said table to a position opposite the matrix, between said table and said face of said matrix, conduits leading pigment under pressure through the matrix to the recesses in the face thereof and onto the sheet whilst the sheet is in the clamped position, means for retaining the sheet in position vertically beneath said matrix, after the sheet has been parted therefrom upon a rising movement of said matrix, and during further movement of said reciprocating table, an extension on said table, endless belts supported on said extension with the upper runs thereof in the plane of the surface of said table and means whereby said belts are rolled beneath the sheet of material held by the retaining device in position beneath said matrix during movement of said reciprocating table away from said matrix, the arrangement being such that the sheet is carried away from beneath said matrix by the belts during a movement of said table towards said matrix and after the sheet has been released by said retaining device.

12. Apparatus for applying pigment to the surface of a number of sheets of paper, cardboard, fabric or other sheet material singly in succession, comprising a matrix having recesses in the face thereof, a horizontally sliding table adapted to feed sheets singly to a position opposite said matrix, a continuously moving driving member for said sliding table, means for uncoupling said table from and coupling said table to said driving member when said table with a sheet thereon is opposite the face of said matrix, means to effect relative movement between said table and said matrix first to clamp the fed sheet against the face of said matrix and subsequently to release it therefrom, conduits leading pigment under pressure through said matrix to the recesses in the face thereof and onto the sheet whilst the sheet is in the clamped position, means for retaining the sheet in position vertically beneath said matrix after the sheet has been parted therefrom and during further movement of said sliding table and means adapted to move the sheet from beneath said matrix during the movement of said table in said direction to feed the next succeeding sheet to the position opposite said matrix.

13. Apparatus for applying pigment to the surface of a number of sheets of paper, cardboard, fabric or other sheet material singly in succession, comprising a matrix having recesses in the face thereof, a horizontally sliding table adapted to feed sheets singly to a position opposite said matrix, driving means for said table including a fixed rack, a rack wheel adapted to roll to and fro thereon continuously, a second rack engaged by said rack wheel and adapted to be moved to and fro continuously by said rack wheel, means for coupling said table with and uncoupling said table from said second rack when said table with a sheet thereon is opposite the face of the matrix, means to effect relative movement between said table and said matrix first to clamp the fed sheet against the face of said matrix and subsequently to re-

lease it therefrom, conduits leading pigment under pressure through said matrix to the recesses in the face thereof and onto the sheet whilst the sheet is in the clamped position, means for retaining the sheet in position vertically beneath said matrix after the sheet has been parted therefrom and during further movement of said sliding table and means adapted to move the sheet from beneath said matrix during the movement of said table in the direction to feed the next succeeding sheet to the position opposite said matrix.

14. Apparatus for applying pigment to the surface of a number of sheets of paper, cardboard, fabric or other sheet material singly in succession, comprising a matrix having recesses in the face thereof, a horizontally sliding table adapted to feed sheets singly to a position opposite said matrix, driving means for said table including a fixed rack, a rack wheel adapted to roll to and fro thereon continuously, longitudinal guides on the underside of said sliding table, a second rack mounted for sliding movements in said guides and adapted to be moved to and fro continuously by said rack wheel, means for coupling said table with and uncoupling said table from said second rack when said table with a sheet thereon is opposite the face of said matrix, means to effect relative movement between said table and said matrix first to clamp the fed sheet against the face of said matrix and subsequently to release it therefrom, conduits leading pigment under pressure through said matrix to the recesses in the face thereof and onto the sheet whilst the sheet is in the clamped position, means for retaining the sheet in position vertically beneath said matrix after the sheet has been parted therefrom and during further movement of said sliding table and means adapted to move the sheet from beneath said matrix during the movement of said table in the direction to feed the next succeeding sheet to the position opposite said matrix.

15. Apparatus for applying pigment to the surface of a number of sheets of paper, cardboard, fabric or other sheet material singly in succession, comprising a matrix having recesses in the face thereof, a horizontally sliding table adapted to feed sheets singly to a position opposite said matrix, a continuously moving driving member for said sliding table, means for uncoupling said table from and coupling said table to said driving member when said table with a sheet thereon is opposite the face of said matrix, a latch device adapted to hold the table stationary when in position opposite said matrix and uncoupled from the continuously moving driving member, and to release said table for movement when said table is coupled to the continuously moving driving member, means to effect relative movement between said table and said matrix first to clamp the fed sheet against the face of said matrix and subsequently to release it therefrom, conduits leading pigment under pressure through said matrix to the recesses in the face thereof and onto the sheet whilst the sheet is in the clamped position, means for retaining the sheet in position vertically beneath said matrix after the sheet has been parted therefrom and during further movement of said sliding table and means adapted to move the sheet from beneath said matrix during the movement of said table in the direction to feed the next succeeding sheet to the position opposite said matrix.

16. Apparatus for applying pigment to the sur-

face of a number of sheets of paper, cardboard, fabric or other sheet material singly in succession, comprising a horizontally reciprocating table, a matrix having recesses in the face thereof, mechanism for moving said matrix vertically towards and away from said table so as to clamp a sheet, fed by said table to a position opposite the matrix, between the table and the face of said matrix, conduits leading pigment under pressure through said matrix to the recesses in the face thereon and onto the sheet whilst the sheet is in the clamped position, valves for starting and stopping the flow of pigment through said conduits whilst said matrix is in the lowered position, means for retaining the sheet in position vertically beneath said matrix, after the sheet has been parted therefrom upon a rising movement of said matrix, and during further movement of said reciprocating table and means adapted to move the sheet from beneath said matrix during a subsequent movement of said table in the direction to feed the next succeeding sheet to the position opposite said matrix.

17. Apparatus for applying pigment to the surface of a number of sheets of paper, cardboard, fabric or other sheet material singly in succession, comprising a matrix having recesses in the face thereof, sheet feeding mechanism adapted to feed sheets singly in succession to a position opposite the face of said matrix, means to effect relative movement between said matrix and a sheet fed by said feeding mechanism first to bring said fed sheet into clamped surface contact with the face of said matrix and subsequently to release it therefrom, conduits leading pigment under pressure through said matrix to the recesses in the face thereof and onto said sheet
- 10 15 while it is in the clamped position, means for retaining the sheet in position vertically beneath said matrix, after it has been released therefrom, for a time interval to permit pigment falling from said matrix to deposit on the appropriate areas of said sheet and means for removing said sheet from beneath said matrix when released by said retaining means.

ALFRED PIERSENNE BATTEY.

Certificate of Correction

Patent No. 2,302,096.

November 17, 1942.

ALFRED PIERSSENE BATTEY

It is hereby certified that errors appear in the printed specification of the above numbered patent requiring correction as follows: Column 1, line 43, beginning with the word "singly" strike out all to and including "applied" in line 48, and insert instead *rate of feed of the sheets is achieved*; and that the said Letters Patent should be read with these corrections therein that the same may conform to the record of the case in the Patent Office.

Signed and sealed this 9th day of November, A. D. 1948.
